UNITED STATES PATENT OFFICE

2,093,001

REFINING NAPHTHENIC ACIDS

Arthur L. Blount, Palos Verdes Estates, Calif., assignor to Union Oil Company of California, Los Angeles, Calif., a corporation of California

Application November 25, 1935, Serial No. 51,500

20 Claims. (Cl. 260—108)

The present invention relates to naphthenic acids, and more particularly to a new process for refining naphthenic acids from alkali wastes obtained from the treatment of petroleum fractions.

Naphthenic acids, such as might be obtained from the alkali wastes arising from the refining of petroleum or shale oil fractions constitute a complex mixture of acidic compounds primarily containing carbon, hydrogen and oxygen. They range from comparatively low boiling liquids to materials which are solid and semi-solid at ordinary temperatures. Their viscosities as well as the boiling points of these substances are directly proportional to the viscosities and boiling points of the hydrocarbon fractions in which they are originally present.

Ordinarily, the alkali wastes containing these naphthenic acids, although substantially unsuitable for further treatment of petroleum fractions, still contain a relatively small amount of caustic soda, being present in amounts substantially equal to about 0.1% by weight of the alkali wastes. In order to remove phenolic materials from said alkali wastes, it is first necessary to neutralize the mixture so that it is neutral to phenolphthalein. Until the present time this neutralization was carried out by the addition of an inorganic acid such as sulfuric acid. However, it was found very difficult and even practically impossible to produce such a neutral mixture by the addition of the inorganic acid, such as sulfuric acid, due to its sludging effect. It was therefore found necessary to add an excess of sulfuric acid and to follow this treatment by a neutralization with caustic soda or a similar alkali until the reaction of the mixture was neutral to phenolphthalein. Obviously, such a procedure is unnecessarily costly, rendering further treatment quite cumbersome. Furthermore, the neutralization of the alkali wastes with sulfuric acid produced sodium sulfates which produced undesirable cakes in the stills employed in the subsequent steps of refining naphthenic acids.

It is therefore one of the objects of the present invention to obviate the above defects and to provide a method which avoids the necessity of using inorganic acids as well as the subsequent neutralization of the thus acidified alkali wastes with an alkali.

The alkali wastes neutralized by the use of an acid comprises an aqueous solution of sodium naphthenates generally containing appreciable quantities of oil and free phenolic materials. Before the sodium naphthenates may be con-

verted into naphthenic acids by acidification, it is first necessary to remove these appreciable quantities of oil and phenolic materials. Until the present time this was carried out by batch distillation. Such a procedure, however, is detrimental to the quality of the final naphthenic acids obtained due to the prolonged cooking of the naphthenate soaps as well as because of the generation of froth which prevents proper distillation.

It is therefore a further object of the present invention to provide a method whereby the removal of the oils and phenolic bodies from the mixture thereof with sodium naphthenate may be carried out without any of the above-mentioned defects and without the undesirable cooking of the naphthenate soaps.

After the above described deoiling and dephenolating, the soaps are then dissolved in water and the thus obtained soap solution is acidified to produce the semi-refined naphthenic acids. This reaction produces a quantity of water thereby necessitating the removal of the semi-refined naphthenic acids from the thus obtained aqueous phase.

The obtained naphthenic acids contain varying amounts of carbonaceous materials, there being as much as three to five per cent and even more of these undesirable materials present. The major portion of these carbonaceous materials exists in a finely suspended or colloidal state and are difficultly removed by settling or centrifuging. The naphthenic acids containing such materials have a dark and turbid color and an undesirable odor, thereby rendering them practically useless as a commercial product.

To produce a commercial product, it has been customary to distill the thus dephenolated and deoiled semi-refined naphthenic acids to remove the admixed carbonaceous material, and then to treat the overhead product to remove therefrom the dark color and foul odor. Such a procedure, however, would not materially improve the color of the overhead product, since the presence of carbon caused the fouling of the stills. To avoid this defect, it has been previously proposed to pre-treat the semi-refined acids, prior to the distillation step, to remove therefrom these undesirable constituents.

It has now been discovered that the above and other objects may be attained by the use of certain steps described hereinbelow, some of these steps being in the form of substitutions for known steps of operation, while others constitute or comprise additional steps to be incorporated into the

known method of refining crude naphthenic acids. Thus, it has been discovered that it is preferred to neutralize the alkali wastes with naphthenic acids themselves instead of the above described step 5 of neutralization with inorganic acids. One of the advantages obtained by such neutralization of the alkali wastes still containing a small percentage of free alkali or sodium phenolates resides in the fact that it is possible to obtain a solution neutral 10 to phenolphthalein by the addition of the naphthenic acids alone without the necessity of following this operation by the addition of further quantities of alkali, as is necessary in the case of the use of inorganic acids. Such use of naphthenic 15 acids avoids the undesirable formation of salt cakes, such as sodium sulfate cakes. Also, the addition of naphthenic acids is not detrimental to the final product since one is dealing with naphthenic acids in the first place so that the 20 naphthenic acids added to the crude naphthenate mixture will be again recovered as naphthenic acids at the end of the refining process. Furthermore, the use of naphthenic acids is advantageous in that it avoids the treatment of highly corrosive 25 mixtures, as is the case when sulfuric acids are employed.

It was further discovered that the distillation 30 of the mixture containing the sodium naphthenates, phenolic materials, oil and water may be realized at lower temperatures than ordinarily necessary for such evaporation, and without any cooking of the naphthenate soaps. This may be accomplished by passing the above-mentioned mixture through some means such as a heat ex- 35 changer or tubular still wherein all of the heat necessary to evaporate the phenols, oil and water is added to the mixture, followed by a flashing of the mixture in a flash chamber wherein the temperature is maintained below a predetermined 40 upper limit to prevent the undesirable cooking of the naphthenate soaps. It has been further discovered that the temperature in the flashing chamber may be kept below the maximum limit by maintaining a body of distillate in said cham- 45 ber, said distillate having a suitable distillation range consistent with the maximum temperature desired in said flashing chamber, as well as by the injection of superheated steam into the flashing chamber during the introduction of the charg- 50 ing stock as well as during the evaporation therefrom of the undesirable oil, water and phenolic materials.

The naphthenate soaps thus produced must 55 then be converted into naphthenic acids, as by water and acid treatment. These semi-refined naphthenic acids contain certain undesirable carbonaceous and color-producing bodies, as well as hydroxy-acids of mediocre oil solubility. Many methods have been proposed to refine the naph- 60 thenic acids to remove these undesirable substances. Thus, the acids may be treated with a solvent, such as a liquefied normally gaseous hydrocarbon. The naphthenic acids being soluble in such a solvent, it is easy to obtain phase separation, and thus remove, as a precipitate, any and 65 all of the above mentioned undesirable materials. To eliminate the hydroxy-acids it may be necessary to chill the naphthenic acid-solvent mixture.

70 Therefore, broadly stated, the present invention may be stated to reside in the neutralization of the alkali wastes by means of naphthenic acids, and the imparting to such neutralized alkali wastes of all of the heat necessary to evaporate 75 the oil, water and phenolic materials contained

therein, followed by the flashing of the thus heated mixture to evaporate said materials without undue cooking of the sodium naphthenates in said mixture.

The invention further resides in neutralizing 5 alkali wastes by adding refined or semi-refined naphthenic acids, imparting to such alkali wastes all of the heat necessary to evaporate the oil, 10 water and phenolic materials contained therein followed by the flashing of the thus heated mixture to separate these materials without the necessity of using the undesirable high temperatures detrimental to the naphthenate soaps, and 15 treating the thus obtained naphthenate soaps to derive therefrom the naphthenic acids.

The invention still further resides in the neutralization of the alkali wastes with naphthenic acids, thus eliminating the ineffective, cumbersome and costly acidification of these alkali wastes with an inorganic acid followed by a neutralization of the mixture with a caustic alkali until reaction of the mixture is neutral to phenolphthalein. The invention still further resides in imparting to the thus neutralized alkali wastes of all the heat necessary to evaporate the oil, 20 water and phenolic materials contained therein, and of flashing said mixture to evaporate said mentioned materials at a temperature which is insufficient to affect undesirably the sodium naphthenates. This phase of operation may be 25 realized by passing the neutralized alkali wastes containing sodium naphthenates, oil, water and free phenolic materials through a heat exchanger or tubular still wherein all the heat necessary to evaporate all the volatile materials is imparted to 30 the mixture. The thus heated mass is then 35 flashed into a chamber to separate all the substances thus volatilized. Such a procedure eliminates the unnecessary and detrimental frothing of the sodium naphthenates (said frothing being 40 an incident to the ordinary batch method of distillation) as well as the undesirable cooking of the sodium soaps at temperatures sufficiently high to affect the quality of the final product. To aid 45 the evaporation of the oil, water and phenolic materials from the neutralized alkali wastes it is frequently necessary to heat the flashing chamber. If such heating is carried out by the use of external heat, the quality of the naphthenic acids 50 may be affected by local overheating. To eliminate this it is proposed to provide in the flashing chamber a bath of material which may be maintained at the desired temperature and which will 55 at the same time prevent such undesirable local overheating of the naphthenate soaps. For this purpose it is possible to use a hydrocarbon fraction having an average boiling temperature of about the temperature necessary to evaporate the materials being flashed. These hydrocarbons will 60 then be evaporated together with the oil, water and phenolic materials, ultimately leaving the sodium naphthenate soaps in a substantially pure state. As an aid to the distillation and evaporation of these materials it is sometimes advisable 65 to employ superheated steam which may be injected into the flashing chamber during the charging thereof with the heated neutralized alkali wastes as well as thereafter during the evaporation of the above mentioned materials. This addition of superheated steam also prevents the 70 undesirable cooking of the naphthenate soaps by permitting the use of lower temperatures as well as shorter distillation periods. Therefore, the invention may still further reside in imparting to 75 the neutralized alkali wastes the heat necessary

to evaporate the above mentioned materials, of flashing the thus heated mixture into a bath maintained at a temperature at which the sodium naphthenates will not be detrimentally affected by heat, and of evaporating all the materials with the exception of the sodium naphthenates at such comparatively low temperature, with or without the injection of superheated steam to aid said distillation and evaporation.

10 It is to be noted that the use of naphthenic acids to neutralize the alkalinity of the alkali wastes avoids the necessity of careful neutralization. This is due to the weak corrosive qualities of naphthenic acids. Thus, when inorganic acids, 15 such as sulfuric acid, are used for this neutralization it is necessary to obtain a mixture which shows a neutral reaction to phenolphthalein due to the highly corrosive action, i. e. strong acidity, of these inorganic acids. On the other hand, the 20 naphthenic acids having a considerably weaker corrosive action, substantially no detrimental effect would occur in using an excess thereof. The present invention, therefore, also covers the use of naphthenic acids not only in quantities sufficient 25 to neutralize the alkali wastes, but also in any other quantities, preferably at least sufficient to neutralize the alkalinity of these wastes.

The invention is illustrated by way of example in the accompanying drawing which discloses diagrammatically a system of refining naphthenic acids according to the process constituting and including the objects of the present invention.

Referring more particularly to the drawing, the alkali wastes such as obtained from the caustic soda solution treatment of petroleum distillates of the type of kerosene, light gas-oil or even lubricating oil distillates, are introduced through line 10 into a container or tank 11. These alkali wastes, although unsuitable for further treating of petroleum distillates, still contain a small percentage of caustic soda, the amount thereof being in the neighborhood of 0.1% by weight of the waste alkali. These waste alkalies are then conveyed through line 12 into a tank 13 wherein they are thoroughly commingled with suitable naphthenic acids introduced through line 14. The quantity and rate of introduction of the naphthenic acids is such that the mixture leaving tank 13 through line 15 shows a substantially neutral reaction to phenolphthalein. This mixture consists of sodium naphthenate soaps containing an appreciable quantity of oil, free phenolic materials, water and possibly a small amount of naphthenic acids.

55 The above mixture is conveyed by pipe 15 into a tubular still or heat exchanger 17 wherein the mixture is heated to a temperature sufficient to evaporate all of the water, oil and phenols, but insufficient to affect detrimentally the sodium naphthenate soaps. This heating may be carried out under any desired and preferred pressure. The thus heated mixture then passes through line 18 into a flashing chamber or still 20. In the preferred form this flashing chamber 20 contains a body of petroleum distillate introduced thereto through line 21, said petroleum distillate having an average boiling temperature substantially equal to the temperature necessary for the evaporation of the oil, water and phenolic materials 35 from the heated waste alkalies introduced into said still through line 18. This petroleum distillate bath is used primarily for the purpose of preventing local overheating of the sodium naphthenates. However, it also inhibits the foaming 50 of these soaps. The petroleum distillate bath is

5
maintained at its boiling point by the application of heat, preferably from an external source (not shown in the drawing) to aid the removal of the oil, water and phenolic material vapors and to cover heat losses, and superheated steam may be introduced into the still 20 through line 23. Obviously, the bath may be external to the still 20. The evolved vapors are removed through line 24, while the sodium naphthenate soaps remaining as the residue in still 20 are removed through line 26. 10

As shown in the drawing, the operation so far constitutes in effect a batch operation. Thus the waste alkalies neutralized in tank 13 and heated to the proper temperature in the coil 17 are introduced into flashing chamber or still 20 until the latter is practically full. Thereafter the introduction of further quantities of heated alkali wastes is stopped and the mixture in the flashing chamber is allowed to boil or is steamed until only the naphthenate soaps remain in the still. The temperature in said still or flashing chamber is maintained at the predetermined upper limit by the boiling of the aforesaid hydrocarbon fraction as well as by the injection of superheated steam both during the charging of the flashing chamber and the evaporation of all the constituents except the sodium naphthenate soaps. However, it is obvious that the operation may be made continuous by providing a plurality of flashing chambers 20 so that the alkali wastes heated in the heating coil 17 may be introduced into one flashing chamber while another is in the stage of evaporation of the undesirable constituents. As a modification, a stripping column may be provided, said column having means for a continuous removal of the soaps.

As stated previously the use of a petroleum distillate bath not only prevents the undesirable overheating and cooking of the sodium naphthenate soaps but also the frothing thereof. In actual practice it has been found that a distillate having an approximate distillation range from 450 to 600° F. produced the desired results since with the injection of superheated steam it was possible to maintain the temperature below 500° F. and still evaporate all the materials with the exception of the naphthenate soaps. 40 45

The sodium naphthenate soaps removed from flashing chamber 20 through line 26 are dissolved in water in an injector 30 into which water is introduced through line 31. The soap solution thus obtained is then conveyed through line 32 into a container 33 wherein the solution is commingled with an inorganic acid such as sulfuric acid introduced through line 35. This acidification results in the production of the so-called semi-refined naphthenic acids. The reaction further produces a certain quantity of water in addition to the water added through line 31 for the purpose of dissolving the naphthenate soaps. The water is then removed through line 31, while the semi-refined naphthenic acids are withdrawn through line 38.

ferred form this flashing chamber 20 contains a body of petroleum distillate introduced thereinto through line 21, said petroleum distillate having an average boiling temperature substantially equal to the temperature necessary for the evaporation of the oil, water and phenolic materials from the heated waste alkalies introduced into said still through line 18. This petroleum distillate bath is used primarily for the purpose of preventing local overheating of the sodium naphthenates. However, it also inhibits the foaming of these soaps. The petroleum distillate bath is 5

a temperature of approximately -30° F. by any of the well known methods of either internal or external refrigeration. Since the naphthenic acids are soluble in cold propane, they will remain in solution while the undesirable carbonaceous and asphaltic materials as well as other color and odor producing substances and hydroxy-acids will precipitate out of solution. These may be removed by any of the well known methods and means, such as centrifuging, filtering or simple decantation. In the diagrammatic drawing the solution of cold propane and naphthenic acids is removed through line 41 while the precipitated undesirable materials are withdrawn through line 42. Since these materials contain some propane, they may be treated for the purpose of recovering this solvent. The naphthenic acid solution in propane is then conveyed through line 41 into a container 43 in which the propane is removed, for example by evaporation, the propane vapors leaving through line 44 while the naphthenic acids freed from substantially all of the undesirable materials are conveyed through line 45 into a vacuum still 46 wherein they are preferably distilled under a pressure of not exceeding 50 mm. of mercury. The desired naphthenic acids having a clear color and a bland odor are removed as the overhead fraction through line 48. After condensation these naphthenic acids are highly suitable for many commercial purposes since they have a light and stable color and a bland odor. The darker color naphthenic acids having a high molecular weight are withdrawn from the vacuum still 46 through line 49.

As a non-limiting example, a five gallon charge of alkali wastes obtained from the caustic alkali treatment of kerosene distillates, was commingled with 330 grams of semi-refined naphthenic acids obtained from alkali wastes similar to the ones being treated. The addition of these naphthenic acids neutralized the alkalinity of the wastes. The mixture was then passed through a heating coil at a rate of about 100 ml. per minute, the mixture being heated in said coil to a temperature in the range of about 400 to 425° F. The thus heated mixture was then introduced into a flashing chamber which contained approximately 1500 ml. of kerosene extract bottoms having a distillation range of approximately 420 to 600° F. Superheated steam was injected into said flashing chamber both during the injection of the heated mixture and during the separation therein of the volatile substances from the naphthenate soaps. The temperature in the flashing chamber was maintained at between 300 and 425° F.

When all of the oil, water and free-phenolic materials were removed, the remaining naphthenate soaps were dissolved in water to produce about seventeen liters of solution. After acidification of the solution with 30% sulfuric acid, and then withdrawal of the aqueous phase, the resulting semi-refined naphthenic acids had an acid number of 278.

Although the drawing discloses a propane treatment of the semi-refined naphthenic acids to remove the undesirable materials, such as asphalts, carboxy- and hydroxy-acids, it is obvious that any other of the well-known methods of refining are also applicable. Thus, in the above-mentioned illustrative example, the semi-refined naphthenic acids were treated with 10% by volume of 80% sulfuric acid, and with 7% of an adsorbent material. The filtered naphthenic

acids had an acid number of 281 and a 6% N. P. A. color, which constitutes a highly desirable naphthenic acid.

As another example, 600 ml. of semi-refined naphthenic acids produced according to the above described method of treatment from alkali wastes obtained from the alkali treatment of gas-oil distillates, were dissolved in about 4 to 5 volumes of liquefied propane, chilled to a temperature of approximately -30° F., and then filtered. This treatment produced 540 ml. of naphthenic acids having an acid number of 256, while the original semi-refined acid had an acid number of 244. The thus treated naphthenic acids were then vacuum distilled to produce, as an overhead fraction, naphthenic acids having a clear color and a bland odor.

Although the above description of the steps of operation are considered to be suitable and advantageous, it is obvious that other steps may be substituted as equivalents or may be added for further refining of the naphthenic acids. For example, it may be desirable to acid treat the naphthenic acids while they are dissolved in propane and prior to the vacuum distillation of said naphthenic acids. Also, it may be advantageous to distill the acids through decolorizing adsorbents such as clays, while said acids are in a vapor phase. Furthermore, the distillates obtained from the vacuum distillation of the naphthenic acids may be clay treated or acid and clay treated or may be contacted with other adsorbent substances such as fuller's earth, for the purpose of obtaining refined acids having a highly desirable pale color and a bland odor.

It is obvious that the naphthenic acids employed for the purpose of neutralizing the alkalinity of the wastes may be taken from the same process. Thus, either the semi-refined naphthenic acids obtained from the acid treatment of the naphthenic soap solution, or the final refined product may be employed for this purpose.

The description of the drawing or of the examples, as well as other specific disclosures occurring herein, are not intended as limitations upon the process constituting the object of the present invention. As to the scope thereof, reference is made to the appended claims.

I claim:

1. A method of refining alkali wastes obtained from petroleum and like fractions to produce refined naphthenic acids, which comprises adding naphthenic acids to said alkali wastes to neutralize the alkalinity thereof, imparting to such neutralized alkali wastes all of the heat necessary to evaporate all of the constituents therein with the exception of naphthenate soaps, separating the thus vaporized volatile materials, and treating the naphthenate soaps to obtain therefrom the naphthenic acids.

2. In a method according to claim 1, wherein the quantity of naphthenic acids added to the alkali wastes is only sufficient to neutralize the alkalinity of said wastes.

3. In a method according to claim 1, wherein the quantity of naphthenic acids added to the alkali wastes is in excess of the quantity necessary to neutralize the alkalinity of said wastes.

4. In a method according to claim 1, wherein the neutralized alkali wastes, containing naphthenate soaps, oil, water and free-phenolic materials, are heated to impart thereto all the heat necessary to evaporate said oil, water and free-phenolic materials, said heat being insufficient to affect detrimentally the naphthenate soaps.

5. In a method according to claim 1, wherein the separation of the volatile materials is carried out in a bath maintained at a temperature such that the naphthenate soaps are not affected detrimentally.

6. In a method of refining alkali wastes obtained from petroleum and like fractions to remove therefrom naphthenic acids, the step of adding naphthenic acids to said alkali wastes.

10 7. In a method according to claim 6, wherein the quantity of added naphthenic acids is sufficient to neutralize the alkalinity of the alkali wastes.

8. In a method according to claim 6, wherein 15 the quantity of naphthenic acids added to the alkali wastes is in excess of the quantity necessary to neutralize the alkalinity of said wastes.

9. In a method of refining alkali wastes obtained from petroleum and like fractions to remove therefrom the naphthenic acids, the steps of neutralizing the alkalinity of said alkali wastes by the addition of naphthenic acids thereto, imparting to said neutralized wastes all of the heat necessary to evaporate therefrom all of 25 the constituents with the exception of the naphthenate soaps, and separating the thus vaporized volatile materials.

10. In a method according to claim 9, wherein in the neutralized alkali wastes, after imparting thereto the heat necessary to evaporate the volatile materials, are introduced into a body maintained at a temperature which prevents any detrimental cooking of the naphthenate soaps contained in the alkali wastes.

35 11. In a method of refining alkali wastes obtained from petroleum and like fractions to remove therefrom naphthenic acids, the steps of adding a naphthenic acid to said wastes to neutralize their alkalinity, imparting to said wastes, 40 containing oil, water, free-phenolic materials and naphthenate soaps, all of the heat necessary to evaporate said oil, water and free-phenolic materials, but insufficient to affect detrimentally said naphthenate soaps, flashing said mixture to separate the vaporized materials, and removing the thus separated materials from the naphthenate soaps.

12. In a method according to claim 11, wherein in the heated materials are flashed into a body 50 maintained at a temperature sufficient to remove all of the volatile materials, but insufficient to affect detrimentally the naphthenate soaps.

13. In a method according to claim 11, wherein in the heated alkali wastes are flashed into a 55 hydrocarbon fraction maintained at a tempera-

ture whereby all of the volatile constituents will be evaporated without any detrimental effect on the naphthenate soaps.

14. In a method according to claim 11, wherein in the heated alkali wastes are flashed into a hydrocarbon fraction having an average boiling temperature of substantially the temperature necessary to evaporate the volatile materials in said alkali wastes.

15. In a method according to claim 11, wherein steam is introduced into the flashed heated alkali wastes to aid in the separation of the volatilized materials from the naphthenate soaps.

16. In a method according to claim 11, wherein in the heated alkali wastes are flashed into a bath maintained at substantially the temperature necessary to evaporate the volatile materials, and wherein steam is introduced into said flashed wastes to aid in the separation of the volatilized materials without any detrimental effect on the naphthenate soaps.

17. A method for refining alkali wastes obtained from petroleum and like fractions to produce naphthenic acids, which comprises adding naphthenic acids to said alkali wastes to neutralize the alkalinity thereof, imparting to such neutralized alkali wastes all of the heat necessary to evaporate substantially all of the constituents therein with the exception of naphthenate soaps, separating the thus vaporized volatile materials, treating the naphthenate soaps to obtain therefrom semi-refined naphthenic acids, and subsequently refining said naphthenic acids to obtain acids having a clear color and a bland odor.

18. In a method according to claim 17, wherein in the semi-refined naphthenic acids are dissolved in a solvent having a preferential solubility for the naphthenic acids, whereby the carbonaceous, asphaltic and color and odor producing bodies may be separated from said acids.

19. In a method according to claim 17, wherein in the semi-refined naphthenic acids are solvent extracted to separate the carbonaceous, asphaltic and color and odor producing bodies, and wherein in the thus treated naphthenic acids are distilled to produce naphthenic acids having a desired acid number, clear color and a bland odor.

20. In a method according to claim 17, wherein in the semi-refined naphthenic acids are dissolved in propane under conditions whereby the carbonaceous, asphaltic and color and odor producing bodies may be separated from said acids.
